UNITED STATES PATENT OFFICE.

MELVIN L. STONE, OF LEWISTON, MAINE, ASSIGNOR TO DRAPER COMPANY, OF HOPEDALE, MASSACHUSETTS, A CORPORATION OF MAINE.

FILLING-END HOLDER FOR WEFT-REPLENISHING LOOMS.

No. 897,426.

Specification of Letters Patent.

Patented Sept. 1, 1908.

Application filed January 22, 1908. Serial No. 412,147.

To all whom it may concern:

Be it known that I, MELVIN L. STONE, a citizen of the United States, and resident of Lewiston, county of Androscoggin, State of Maine, have invented an Improvement in Filling-End Holders for Weft-Replenishing Looms, of which the following description, in connection with the accompanying drawing, is a specification, like letters on the drawing representing like parts.

This invention relates particularly to the filling-feeder or magazine in automatic looms of the Northrop type, wherein the supply of filling-carriers in reserve is contained in a movable feeder or magazine, from which they are transferred one by one to the running shuttle. A loom of this type is shown in United States Patent No. 529940, granted to J. H. Northrop November 27, 1894.

The typical form of filling-feeder has at its outer end a bell-like circular plate over which the filling-ends are led and secured at their extremities to a central knob-like end-holder mounted on the feeder.

The waste filling accumulates on the end-holder in a tightly wound mass, and must be removed from time to time by the weaver. Sometimes the end-holder is removed and the waste removed by main force, and frequently the weaver cuts or hacks off the mass of waste with a knife, whether or not the end-holder be removed from the filling-feeder. As the end-holder is made of metal the edge of a knife used as specified is soon turned or dulled.

My present invention has for its object the production of an end-holder from which the waste filling can be readily removed without detaching the holder from the feeder, the waste being removed easily and quickly with the aid of a knife and without injury to the latter.

Figure 1 is a vertical diametrical section through the hub and bell-like circular plate at the outer end of the filling-feeder, with a filling-end holder applied thereto embodying one form of my invention; Fig. 2 is an enlarged outer end elevation of the end holder; Fig. 3 is a side elevation and partial section of the end holder, to more clearly illustrate the invention.

The bell-like filling-end supporting plate b' , Fig. 1, having a hub b'' extended at its outer end at b^3 and apertured to receive the end of the shank of the end holder, is of well

known construction, said plate in practice being mounted to rotate with the main portion of the filling-feeder, as is usual in the Northrop type of loom.

The filling-end holder comprises a circular enlarged or knob-like head 1, and an elongated and slightly tapered shank 2 usually reduced at 3 to enter the end b^3 of the hub, secured therein in any suitable manner, as by a set-screw 4, Fig. 1, the end holder being made as a casting.

In accordance with my present invention I provide the shank with a longitudinal groove 5, preferably somewhat more than semi-circular in cross-section, and I slot the head 1 radially at 6, intersecting the groove.

Into the groove I drive a piece or strip 7 of non-metallic material, such as wood, the outer end of the strip being preferably extended through the slot 6, as shown in Fig. 3, and I prefer to flatten the exposed face of the strip, as at 8. The shape of the groove in cross-section holds the strip firmly in position without other fastening means.

Referring to Fig. 1 the ends of the filling threads are wound around the shank 2, as at f'' , and gradually a mass of waste yarn is formed, which must be removed. To do this the weaver takes a knife and draws it along the shank 2 lengthwise, the point of the knife drawing along the face 8 of the strip 7 of wood, and the filling mass is quickly and cleanly cut completely through, the stroke of the knife blade being continued through the slot 6. This slot also serves to indicate to the weaver the location of the strip of non-metallic material if the filling mass is completely covering the shank of the end holder. The arrangement obviates dulling of the knife blade, it insures a cleaner and more complete cutting of the waste, and removal of the end-holder to remove the waste by stripping is obviated.

Having fully described my invention, what I claim as new and desire to secure by Letters Patent is:—

1. A filling-feeder for filling-replenishing looms provided with a hub at its outer end, a filling-end holder having a metallic shank sustained by the hub, and a non-metallic piece inserted in and extended longitudinally of the shank, along which the blade of a knife may be drawn to cut the accumulated filling-ends therefrom.

2. A filling-feeder for filling-replenishing

looms, a filling-end holder having an enlarged circular head and a metallic shank sustained at the outer end of the feeder, the head having a radial slot, and a strip of non-metallic material inserted in the shank and extended longitudinally thereof in alinement with the slot in the head, for the purpose set forth.

3. A rotatable filling-feeder for filling-replenishing looms, a filling-end holder sustained at the outer end thereof and comprising a longitudinally grooved metallic shank and an enlarged circular head having a radial slot intersecting the groove, and a strip of wood inserted in the groove and at its outer end projecting through the slot.

4. A rotatable filling-feeder for filling-re-

plenishing looms, a filling-end holder sustained at the outer end thereof and comprising a longitudinally grooved metallic shank and an enlarged circular head having a radial slot intersecting the groove, and a strip of non-metallic material inserted in the groove and extended the length of the shank, the outer face of said strip being flattened.

In testimony whereof, I have signed my name to this specification, in the presence of two subscribing witnesses.

MELVIN L. STONE.
